UNITED STATES PATENT OFFICE

GORDON B. MACKE, OF WASHINGTON, DISTRICT OF COLUMBIA

VENDING MACHINE

Application filed May 10, 1929. Serial No. 362,069.

This invention relates to improvements in vending machines especially adapted for use in connection with coin controlled vending machines.

5 In machines of the above character, the operator will sometimes receive an article before the operation of the machine has been fully completed and the mechanism will stop in such position that the machine will apparently be locked, so that a subsequent operator will not receive an article even though a proper coin has been deposited.

10 The primary object of the present invention is to overcome this defect by providing 15 means to prevent the delivery of an article until the complete cycle of operation of the machine has been fully completed, so that the operator or customer will be obliged to 20 complete the operation and leave the machine in proper condition for subsequent operation.

With the above and other objects in view, the invention further includes the following 25 novel features and details of construction, to be hereinafter more fully described, illustrated in the accompanying drawings and pointed out in the appended claim.

In the drawings:—

Figure 1 is a fragmentary sectional view 30 showing a portion of a vending machine with the invention applied, the invention being in its active position.

Figure 2 is a similar view showing the 35 normal position of the parts, the dotted lines illustrating an article released for delivery.

Figure 3 is a sectional view showing a 40 fragmentary portion of a vending machine of a different character with the invention applied.

Figure 4 is a sectional view illustrating the 45 invention applied to another type of machine.

Referring to the drawings in detail wherein like characters of reference denote corresponding parts, the reference character 10 indicates the housing of a vending machine within which is arranged a magazine 11. This magazine is adapted to contain packages or other articles 12 which are delivered 50 through the operation of mechanism to be

described, and the operation of the said mechanism may be coin controlled. As the coin mechanism forms no part of the present invention, such mechanism is not illustrated.

55 The articles 12 are adapted to be ejected from the lower end of the magazine 11 into a delivery compartment 13, so that the customer or operator may receive his article from this compartment. For this purpose, there is provided an ejector mechanism of suitable character. This mechanism as shown in Figures 1 and 2 of the drawings may consist of a slide 14 which is movable within a guide 15 and this slide has connected thereto 60 an operating knob 16. The knob 16 extends upward through a slot (not shown) provided in the housing and is provided with a finger piece whereby the customer or operator may move the slide. Secured to the 65 slide is an ejector 17 which is adapted to pass into the lower end of the magazine through a slot 18. Inward movement of the ejector 17 is yieldingly resisted by a 70 spring 19.

75 The bottom of the magazine is provided with an opening for the passage of the articles 12, the articles passing horizontally outward from the magazine. The articles are supported upon ledges 20 which extend 80 along each side of the slot 18, so that the articles will not fall downward. Horizontal outward movement of the articles is yieldingly resisted by means of a spring arm 21.

85 By reference to Figure 1 of the drawings it will be seen that when the arm 16 is pushed inward against the action of the spring 19, the ejector will engage the lowermost article 12 and force the latter horizontally outward.

90 In order to prevent the article from falling downward into the delivery compartment 13 as soon as the article passes from the ledge 20, the invention provides a substantially L-shaped plate. This plate is 95 normally arranged as shown in Figure 2 of the drawings, being pivotally mounted as shown at 22. As the ejector 17 is moved inward against the action of the spring 19, it will engage the arm 23 of the L-shaped 100

plate and will force this arm downward so as to move the arm 24 upward beneath the outwardly moving article 12 and prevent said article from falling downward into the 5 delivery compartment as shown in Figure 1 of the drawings. The arm 24 will remain in this position until the ejector 17 is retracted, so that the article will not be released until the ejector has been returned to its normal 10 position. The arm 24 of the L-shaped plate 10 is shaped to facilitate passage of the article after the release of the L-shaped plate.

Upward movement of the arm 23 is limited by contact with the guide 15, while outward or return movement of the ejector is limited by stop pins 25 which extend from the ejector and engage upon opposite sides of the slot 18.

In Figure 3 of the drawings the ejector 20 26 is shown in the form of a horizontally 20 slidable frame. This frame has extending therefrom an arm 27 which operates through a slot 28 provided in the housing of the machine. A stationary bottom 29 is provided 25 at the lower end of the magazine 30, so that the lowermost article within the magazine will be positioned within the frame 26.

Pivottally mounted within the housing as shown at 31 is a plate 32. This plate 30 extends into the delivery compartment 33 of the machine and is provided with an extension 34. This extension is engaged by the inclined edge 35 of the projection 36 which is carried by and movable with the ejector 35 frame 26.

Normally the parts are arranged as shown in Figure 3 of the drawings, the extension 34 of the plate 32 being engaged by the inclined edge 35 of the member 26. When the 40 slide is moved outward to the position shown by the dotted lines in Figure 3, the inclined edge 35 of the member 36 will force the extension 34 downward and the plate 32 upward, so that the said plate will receive the 45 article from the ejector 26 and will retain the same until the ejector has been returned to its normal position.

In Figure 4 of the drawings, the vending machine is shown as including a rotary magazine 37 having peripheral pockets 38 which 50 are adapted to contain the articles 39 to be vended. These articles are retained in place by means of a retaining strip 40 until they reach an opening 41 provided in the 55 delivery chute 42. Pivottally mounted within this chute as shown at 43 is a plate 44 which normally occupies the position shown by the dotted lines. A rod 45 is slidingly mounted so that its inner end engages the 60 plate 44 and when this rod is moved inward, the plate 44 will occupy the full line position shown in Figure 4 of the drawings so as to prevent the passage of an article through the delivery chute.

65 In this form of the invention, the coin

mechanism may control the operation of the rod 45 and the magazine 37, so that when the rod 45 is moved inward to the position shown, the article released from the magazine will fall upon the rod and its passage through the delivery chute to the discharge end thereof will be prevented until the rod has been moved outward to its normal position and the plate 44 downward to the dotted line position mentioned.

70 The invention is susceptible of various changes in its form, proportions and minor details of construction and the right is herein reserved to make such changes as properly fall within the scope of the appended 75 claim.

Having described the invention what is claimed is:—

In a vending machine, a housing, an article magazine therein, a reciprocatory ejector arranged to eject articles singly from the magazine, a pivotally mounted plate in the housing and having angularly related portions providing an ejector-engaging arm and an article receiving and supporting arm, 85 said ejector engaging arm adapted to be engaged by the ejector during the ejecting and returning movements thereof to position the receiving and supporting arm to receive the ejected articles from the magazine and support the latter against delivery from the housing until said ejector returns to its non-ejecting position.

90 In testimony whereof I affix my signature.
GORDON B. MACKE.
